UNITED STATES PATENT OFFICE.

CLAUD E. FULLER, OF NEW YORK, N. Y., ASSIGNOR TO NEW YORK BRICK HANDLING CORPORATION, OF NEW YORK, N. Y., A CORPORATION OF NEW YORK.

SHRINKAGE-MEASURING DEVICE.

Application filed August 9, 1926. Serial No. 128,042.

My present invention relates to the manufacture of bricks, and more particularly to an improved method of and apparatus for determining the amount of shrinkage in a 5 kiln caused by the burning operation. One of the principal methods used to determine the intensity or amount of fire applied in the burning of a kiln of brick is the measurement of the settle or shrinkage of the kiln 10 and this measurement takes several forms, depending on the type of kiln used, the most important one in the western territory of the United States being the use of a series or levels of targets that are suspended from 15 the roof of the kiln shed so as to just touch the top of the kiln of brick before the fires are started. As the kiln of brick shrinks, because of the heat applied the distance between the level or target and the top of the 20 brick is measured to thus determine the amount of shrinkage. This method has the disadvantage of requiring the operator to climb to the top of the kiln and make his measurement, the top of the kiln ordinarily 25 being extremely hot with the result that in a great many instances the work is shirked and therefore it is doubtful if accurate measurement of the kiln is known at the present day.

30 In my present invention I have devised an improved method of, and apparatus for, measuring the shrinkage that takes place in a kiln during the burning thereof and utilize in connection with such mechanism, indicating mechanism located at points readily 35 accessible and visible to the operator on the floor of the kiln shed. In the patent granted to me No. 1,548,795, dated August 4, 1925, there is described and claimed a portable kiln bracing post primarily designed for use in a wide span kiln shed and which would permit the usual overhead crane to travel over the top of the kiln. The tie-rods used in this system of bracing disclosed in 40 my patent above referred to are drawn up fairly tight at the beginning of the burn, but when the kiln begins to move under the influence of heat, such tie-rods sometimes get very tight so that it is not possible to attach thereto the usual levels or targets heretofore employed. Further, if the ordinary 45 levels or targets are suspended from the roof of the kiln shed, then it is impossible for the now usual and ordinary traveling crane to pass over the kiln during the burning period.

I find that by substituting I-beams for the tie-rods, in my patent above referred to, that I provide a supporting structure for shrinkage indicating means and also allow the passage over the kiln of the ordinary traveling 60 crane. I may provide a plurality of indicating means and connect such indicating means to an indicating mechanism located along the side walls of the kiln so that the operator, by walking around the kiln, can 65 observe the shrinkage taking place at any point thereof.

The object of my invention, therefore, is an improved method of, and apparatus for, visually indicating the shrinkage in a kiln 70 of brick.

In the accompanying drawings illustrating the preferred embodiment of my invention,

Fig. 1 is a side elevation, and

Fig. 2 is an enlarged front elevation of the indicating mechanism employed.

Referring to the drawings, 10 designates side members of a kiln shed, these side members supporting the roof structure 11. Adjacent to the top of the side members 11 and extending along the inner side of the walls formed thereby are parallelly arranged tracks 12 on which run the supporting and propelling wheels 13 of the usual overhead crane structure 14. Parallel to, but spaced apart from, one of the walls 10, is a temporary side wall composed of members 15, such as are described and claimed in my prior patent above referred to, and extending 80 between the members 15 and one of the side walls composed of the members 10 are I-beams 17, but one of which is shown, it being understood that the others are arranged parallel to and, therefore, are in behind the I-beam shown. The members 15, are, therefore, tied to the side walls comprised of the members 10 in the manner described and claimed in my patent above referred to. Secured to the middle lower portion of each of the parallelly arranged I-beams 17 are bearing blocks 18, the bearing blocks being in alignment with each other and through each bearing block passes a pipe 85 or rod 19. Suspended from the pipe or rod 19, at intervals along its length, preferably about four feet apart, and therefore at intervals along the length of the kiln, which is designated by the numeral 20, are levels or targets 21, but one of which is shown. For 100

105

110

the purpose of suspending the targets or levels 21, I preferably employ a light chain 22.

The critical part of the settling of the kiln takes place on the quarters or sides of the kiln and to measure such settling I have, adjacent to each end of each of the I-beams 17, placed a plurality of bearing blocks 23, the bearings at each end being in alinement with each other, and in each series of bearings I place pipes or rods 24 extending longitudinally of the kiln. From each of the pipes 24 at intervals along the length thereof are suspended, by means of chains 25, rods or pipes 26 and to one end of each of the pipes is pivotally mounted a shoe 27. To the other end of each of the pipes 26 is pivotally attached the upper end of a downwardly extending wire or rod 28, and to this rod or wire 28, adjacent its lower end, is secured an indicating hand or pointer 29. Secured to the sides of the kiln walls formed by the members 15 or side walls 10 are indicator boards 30, there being one of such indicator boards for each of the downwardly extending wires or rods 28. Each indicator board is provided with graduations 31 with which the indicator hand or pointer 29 is associated, and also each indicator board top and bottom is provided with bearings 32, through which the rods or wires 28 may slide.

The plurality of levels 21 operate in the well-known manner of other levels or tar-

gets and ordinarily is quite inaccessible to the operator. As the critical part of the settling takes place, as above stated, in the quarters or sides of the kiln, the shoes 27 follow the movement of the kiln at these points and such movement is transmitted through the rods 26 and the amount of such movement is visually indicated to the operator by means of the pointer 29 and graduations 31. This method permits the travel of the crane 14 the full length of the kiln shed. The arrangement is such that it is easily removed from the portable siding 15 when it is desired to dismantle the kiln and is as easily attached to the siding when the kiln is built in place.

Having thus described my invention, what I claim as new is:

The combination, with a kiln, of a wall located adjacent thereto, a second and temporary wall on the opposite side of said kiln, supports connecting the top of said second wall with the first said wall, a plurality of shrinkage measuring instruments carried by said supports, an indicating instrument mounted on the walls and means for connecting the measuring instruments with the indicators whereby the extent of movement of the measuring instrument is visually indicated on the indicator.

In testimony whereof, I have signed my name to this specification.

CLAUD E. FULLER.
